UNITED STATES PATENT OFFICE.

JOSEPH BAKOVICH, OF HERMINIE, PENNSYLVANIA.

RAIL-JOINT AND FASTENER THEREFOR.

1,374,804.

Specification of Letters Patent. Patented Apr. 12, 1921.

Application filed February 2, 1921. Serial No. 441,880.

To all whom it may concern:

Be it known that I, JOSEPH BAKOVICH, a citizen of Jugo-Slavia, residing at Herminie, in the county of Westmoreland and State of 5 Pennsylvania, have invented certain new and useful Improvements in Rail-Joints and Fasteners Therefor, of which the following is a specification.

This invention relates to certain new and 10 useful improvements in rail joints and fasteners therefor, wherein fastening members lock the rail ends to a tie and directly engage the rail flanges and upper supporting plate of a tie.

15 A further object of the invention is to provide in a rail joint, fastening members of substantially V-shaped formation having the looped portions thereof engaging the rail webs, and wherein the free ends of the 20 fasteners are anchored to a rail tie.

A still further object of the invention resides in the provision of a fastening member for rail joints wherein the fastening members are employed in duplicate and are 25 of like construction, and also enabling the manufacture of independent tie fastening devices of identical construction.

With the above and other objects in view, the present invention consists of the novel 30 form, combination and arrangement of parts hereinafter more fully described in connection with the accompanying drawings and in which like reference characters indicate similar parts throughout the several views.

35 In the drawings,

Figure 1 is a fragmentary side elevational view of a rail joint showing an I-beam supporting tie in section and with the improved fastening devices securing the meeting rail 40 ends to the tie,

Fig. 2 is a top plan view of the construction shown in Fig. 1 with the rail ends in longitudinal horizontal section,

Fig. 3 is a vertical cross sectional view 45 taken on line III—III of Fig. 1, and

Fig. 4 is a fragmentary top plan view of a tie constructed in accordance with this invention.

Referring more in detail to the accom- 50 panying drawings, there is illustrated a rail joint and fastener secured upon a supporting tie in the form of an I-beam including a vertical web 1, base flanges 2 and an upper tread 3 for supporting the rail ends. The 55 rails are of standard construction, embody-

ing webs 4, base flanges 5 and treads 6, the meeting ends of the rails being centrally positioned transversely of the tread 3 of the supporting ties, as shown in Figs. 1 and 2.

The rail fastening bars are of identical 60 construction, and are substantially of V-formation, each fastener comprising a central portion 7 having inclined extensions 8. An opening 10 is provided in the web 4 of each rail end, said openings being in different horizontal planes and through which the central portion 7 of the fastener freely extends. The free ends of the fastener are threaded as at 11 and freely extend through diagonal slots 12 provided in the edges of 70 the tread 3 of the tie while spacing collars 13 are loosely mounted on the projecting threaded ends 11 with the upper faces thereof beveled for engagement with the under face of the tie tread 3 with the outer faces 75 thereof extending transversely of the longitudinal axis of the ends 11 for frictional engagement by the fastening nuts 14 threaded on the ends 11 of said fasteners.

When the rail ends are connected by the 80 V-shaped fastening members, the intermediate bent portions 7 of the fastening members are positioned in the openings 10 of the rail webs. The openings 10 being in different horizontal planes, facilitates the mounting 85 of the fastening members so that one of said members will overlie the other as clearly shown in Figs. 1 and 2. The diagonal slots 12 opening at the edges of the tie seat 3 will permit a pivotal movement of the fastening 90 member within the web opening 10 so that the fastening member in being moved downwardly will have the threaded ends thereof received into said slots to project beneath the tread 3 of the tie. The collars 13 are then 95 freely mounted on the threaded ends 11 of the fastening members and moved to engagement with the bottom face of the tie tread 3 by the clamping nuts 14. With this construction, the rail ends are securely anchored 100 to the supporting tie in the absence of fish plates and supporting chairs while the fastening members 7 alone anchor the rail ends to the tie.

While there is herein shown and described 105 the preferred embodiment of the invention, it is nevertheless to be understood that minor changes may be made without departing from the spirit and scope of the invention as claimed.

What is claimed as new is:

1. A rail joint and fastener comprising meeting rail ends having an aperture in each web portion, V-shaped fastening members 5 passing through said apertures, a supporting tie for the rail ends and means for anchoring the ends of the fastening members to the tie.
2. The combination with meeting rail ends 10 having apertured web portions and an I-beam supporting tie therefor, of fastening members passing through spaced rail web openings and anchored to the upper flanges of the I-beam tie.

3. The combination with meeting rail ends 15 having apertured web portions and an I-beam supporting tie, of V-shaped fastening members extending through the rail web apertures, the upper flange of the I-beam supporting tie having diagonal edge slots 20 therein through which the ends of the fastening members pass, spacing collars on the ends of said fastening members beneath the flange of the tie and securing nuts on the ends of said fastening members.

25

In testimony whereof I affix my signature.

JOSEPH BAKOVICH.
